UNITED STATES PATENT OFFICE

2,487,013

PORTABLE RADIO RECEIVER

Frank A. Zibelman, Chicago, Ill.

Application November 14, 1946, Serial No. 709,732

1 Claim. (Cl. 250—14)

1

This invention relates to certain new and useful improvements in portable radios.

More particularly, the invention has reference to a radio built into a casing or housing, the latter having the form of a cradle type telephone.

An object of the invention is the provision of a portable radio in this form which will be compact, and of a substantially small structure, permitting the same to be placed upon a desk, lamp table, or other supporting pedestal for convenient and immediate use by the user.

Another and equally important object of the invention is the provision of a radio having a station selector dial which simulates the dial of an automatic telephone and which selector dial, in its relationship to the enclosure of the radio instruments, is in position for convenient and ready use.

A radio having its housing or cabinet simulating that of a telephone of the cradle type, must, because of the size of the cabinet, be compact to permit its ready assembly within the cabinet. To facilitate this assembly, one of the objects of the invention is to provide an arrangement for mounting the speaker directly beneath the selector switch and dial and utilizing the periphery of the speaker assembly as a means for supporting the selector switch and dial.

Still another object of the invention resides in the manner of mounting the speaker assembly within the cabinet.

Another object of the invention is the provision of a simple and easily operated arrangement, whereby reception may be had through the telephone receiver or through the speaker assembly, it being the object to control the reception through this telephone receiver or speaker assembly by a switch assembly in turn controlled by the telephone receiver.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of my portable radio illustrating its preferred form of construction;

Fig. 2 is a fragmentary sectional detail view illustrating the receiver cradle and switch assembly actuated by the receiver;

Fig. 3 is a fragmentary sectional detail view similar to Fig. 2 but showing the receiver removed from its cradle;

Fig. 4 is a side elevational view of the speaker assembly;

Fig. 5 is a perspective view of the radio apparatus removed from its cabinet; and

Fig. 6 is a schematic diagram of a proposed selector switch employed in the invention.

5 The several objects of my invention are accomplished by the preferred form of construction shown in the accompanying drawings and in which a mounting plate is indicated at 10. This mounting plate includes cushion feet 11 attached thereto in any suitable manner, whereby to support the mounting plate 10 above a supporting surface in a manner such as to prevent scratching of the surface.

10 On this mounting plate 10 are arranged the various electronic instruments indicated as a complete unit at 12, the radio circuit of which may be of any approved or standard circuit in which there is preferably utilized, in lieu of a variable condenser, what is known as paddle condensers, which latter condensers are well known in the art and are of the type which, when adjusted, become fixed to a predetermined wavelength.

15 This circuit, for the purpose of illustrating this invention, may be said to comprise an antenna circuit and an oscillating circuit and the circuit preferably includes a speaker assembly 13 and a volume switch 14, the latter including an operating shaft 15. The speaker assembly includes a cone 16 having an annular flange 17. Fixed to this flange 17, as at 18, is a cross bar 19. This cross bar 19 supports a selector switch 20 of any approved type or standard construction, which includes a shaft 21. This shaft 21 projects through a sleeve 22, the exterior of which is threaded. A disc 24 is mounted on the sleeve 22 and spaced from the bar 19 by a nut 25. Fixed to this disc 24 is a plate 26, which plate 26 simulates the outer dial plate of a standard automatic telephone, the plate 26 being provided with spaced finger openings 27. The shaft 21 projects into this plate 26 as at 28 and has secured to the end thereof, by means of a set screw 29, a collar 30. The collar 30 is formed as an integral part of the selector plate 26, whereby upon rotation of this plate 26, the shaft 21 and the disc 24 will rotate therewith, the shaft 21 being rotated to actuate the selector switch 20.

20 I have not illustrated the internal structure of this selector switch, as such structure does not constitute per se any part of the present invention. For purposes of illustration of this invention, it need only be pointed out that such switch should include a shaft such as the shaft 21 for rotating a contact carrying disc 24', diagrammatically illustrated in Fig. 6, the contacts 22' of which plate are arranged in pairs with each contact of a pair adapted to engage a fixed bridging conductor plate 23' upon positioning of a particular pair of contacts upon said conductor plate by movement of the plate 26, the contacts having connection in any suitable manner to their respective circuit wires 24' of the radio circuit.

25 The mounting plate 10, with the speaker as-

sembly 13 and radio parts mounted thereon, is assembled within a cabinet 31. In the present instance, this cabinet 31 is in the form of a desk telephone of the cradle type, including opposite walls 32 and 33 slanting inwardly toward each other and merging together to provide a cradle 34 on which a receiver 35 is adapted to be supported.

The speaker assembly 13 is mounted upon the plate 10 by means of a bracket 36 attached to this speaker assembly 13 in any suitable manner as by welding or the like and secured to the plate 10 by means of screws 37.

When the speaker assembly is thus mounted on the plate 10, the entire unit is arranged within the cabinet 31 by positioning the disc 24 and selector plate 26 within the confines of a depending collar 38 formed in the wall 32 of the cabinet 31. In arranging this assembly, the shaft 15 is projected through an opening 39 formed in the base portion 40 of the front wall 32. On the projecting end portion of the shaft 15 is a finger knob 41. Carried by a wall of the cabinet 31 and overlying the sloping front wall 32 is a limiting finger 42 arranged in the line of path of movement of the marginal edge of the selector plate 26, in which the openings 27 are formed.

In the base of the rear wall 33 is formed an opening 43, through which the power cord 44 projects for connection with a wall socket (not shown).

Within the cradle 34 is arranged a supporting bracket 45 carrying a switch assembly 46 incorporated in the circuit of the radio unit 12 by conductors 47. This switch assembly 46 includes oppositely disposed leaf springs 48 and an intermediate leaf spring 49 adapted to normally have contact with the upper of the leaf springs 48 when the receiver 35 is removed from the cradle 34. In opposite end portions of the cradle 34 are arranged mounting blocks 50, each carrying cushioning means for the receiver 35 in the form of plunger pins 51, having associated therewith springs 52 to resist their movement in a downward direction under the weight of the receiver 35. I utilize one of these plunger pins 51 to actuate the intermediate leaf spring 49 whereby to disengage the same from the upper of the spring leaves 48 and move the intermediate leaf spring 49 into contact with the lower of the leaf springs 48, in which position the speaker assembly 13 is in circuit with the radio receiving unit 12 for reception through the speaker assembly 13 instead of through the receiver 35. The receiver 35 is connected by the conductors 53 into the circuit of the radio unit 12.

On the disc 24, beneath the openings 27, there may be printed, engraved, or embossed station identification indicia so that the user may be in a position to select a station he desires to listen to. This is done by placing the finger in the opening 27, through which the indicia of the station desired appears, and rotating the selector plate 26 until the finger engages the limiting finger 42, to which position of the plate 26 the selected station will be receivable.

From the foregoing description, it will be ap-

parent that when the receiver 35 is on the cradle 34, the speaker assembly 13 will be in circuit with the radio unit 12. However, when the receiver 35 is not upon the cradle 34, the receiver 35 will be in circuit in the radio unit 12. This permits one to use the ear phones in lieu of the speaker assembly 13. This arrangement is especially useful in places where reception is interfered with because of surrounding noises or in lounges, hospitals or hotels where the use of the speaker assembly 13 might disturb those nearby. In other words, the arrangement gives to the user individual selection and reception of radio entertainment.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

A portable radio receiving set comprising a cabinet formed to simulate a telephone stand of the cradle type having a front wall inclined rearwardly from the base thereof and provided with an opening in said wall, a loudspeaker mounted within said cabinet and directly behind said opening with its diaphragm substantially parallel to said inclined face, a tunable radio receiving apparatus housed within said cabinet, a tuning control unit mounted within said cabinet and connected to said apparatus to adjust the same to receive desired frequencies, a perforate station-selector dial mounted to lie adjacent said opening and substantially flush with said inclined wall, and a mechanical connection between said dial and said tuning control, whereby sound produced by said loudspeaker will be directed substantially in the direction of a person in position to operate said station-selector dial, a receiver unit simulating a telephone handset removably supported upon said cabinet, and a switch positioned beneath said unit and adapted for operation by the weight of said receiver unit, said switch being connected with said receiving apparatus, said receiver unit and said loudspeaker for alternatively connecting one or the other of the latter respectively with said receiving apparatus when said receiver unit is removed from or replaced in its supported position on said cabinet.
